UNITED STATES PATENT OFFICE.

ROBERT MALLU, OF NEW ORLEANS, LOUISIANA, ASSIGNOR TO THE MALLU SHEET METAL WORKS, OF NEW ORLEANS, LOUISIANA.

RAT GUARD.

Application filed May 4, 1925. Serial No. 27,890.

To all whom it may concern:

Be it known that I, ROBERT MALLU, a citizen of the United States, and a resident of New Orleans, in the parish of Orleans 5 and State of Louisiana, have invented certain new and useful Improvements in Rat Guards, of which the following is a specification.

This invention relates to an improvement 10 in rat guards especially adapted for use with cables or hawsers employed in tying ships to docks, wharves or the like.

The object of the invention is to provide a rat guard of this character in which all 15 bolts, nuts and the like are eliminated and which is adjustable to fit any size of hawser or cable and which may be positively and securely fastened in the desired position on the cable.

Another object is to provide a device of 20 this character which is of extremely simple and durable construction, reliable in use and easy and comparatively inexpensive to manufacture.

Other objects and advantages of the 25 invention reside in certain novel features of construction, combination and arrangement of parts which will be hereinafter more fully described and particularly pointed out 30 in the appended claims, reference being had to the accompanying drawings forming part of this specification, and in which:

Figure 1 is a view in elevation, illustrating the preferred embodiment of the invention;

Figure 2 is a perspective view in transverse section on line 2—2 of Figure 1;

Figure 3 is a fragmentary view in perspective, illustrating the construction of the 40 means for securing the guard in position and for obstructing the central opening of the guard proper; and

Figure 4 is a detail view in section on line 4—4 of Figure 1.

Referring to the drawings wherein for the sake of illustration is shown the preferred embodiment of the invention, it will be seen that the rat guard comprises a disk 10 which is preferably constructed of light 45 weight imperforate sheet metal, galvanized or otherwise treated so as to be better adapted to withstand the action of the elements. As shown in the drawings the disk 10 is formed with a central opening 11 and is 50 slit or cut radially from the opening to its

periphery at one point in the circumference of the disk and the adjacent radial edges 13 and 14 which are thus formed overlap, as shown in Figures 1 and 4. The edges 13 and 14 are maintained in this overlapping 60 relation by means of a catch designated generally at 15 and including a keeper 16 carried by the edge 14 and overlying the edge 13 and having an inclined keeper plate 17 (see Fig. 4). A latch 18 is fixed to the edge 13 and underlies the keeper 16, the latch having an inclined latch plate 19 which coacts with the inclined keeper plate 17 of the keeper 16. It is obvious that while the disk 10 may be adjusted so as to 65 overlap the edges more or less the edges 13 and 14 are prevented from being disassociated by the action of the inclined latch plate 19 and inclined keeper 17. As illustrated in Figure 2, the disk 10 is adapted 70 to be positioned upon a cable or hawser running from the ship dock or the like and indicated at C. The cable C extends through the opening 11 of the disk 10, and means is provided for securing the disk to 75 the cable and for obstructing the space between the wall of the opening 11 and the periphery of the cable. This means preferably comprises a plurality of attaching arms 20 arranged in circular series around 80 the opening 11. The arms 20 are pivotally connected, as at 21, to attaching plates 22 which are riveted or otherwise secured, as at 23, to the disk 10 and in this manner the arms 20 are pivotally connected to the disk 85 10. The arms 20 and attaching plates 22 and their pivotal connection preferably take 90 the form of a hinge, as shown in the drawings. The outer ends of the arms 20 are formed with eyes 25, the axes of which may 95 be arranged to lie in the same circle and these eyes receive a flexible element 26 such as a cord or the like, one end of which is knotted, as at 26^a so as to fix one end of 100 the flexible element. Then when the flexible element 26 is drawn tight, the arms 20 may be made to snugly engage the cable C, as shown in Figure 2, and when so engaged the free end of the flexible element may be tied or knotted with the cable C or with 105 another portion of the flexible element to secure the arms in the position shown. It is to be understood that the flexible element 26 may be of sufficient length to provide for wrapping it around the arms 20 several 110

times if such should be desired. Adjacent the eyes 25 a portion of the metal which constitutes the attaching arms 20 is struck inwardly to provide prongs 27 which penetrate or tie into the cables C to complete the attachment of the guard in position. In this manner the arms 20 and associated elements serve not only to secure the guard in position but also to effectively obstruct 10 the space or opening between the wall of the opening 11 and the periphery of the cable C thereby preventing the rats from passing through this space.

The guard may be readily positioned 15 around the cable and securely maintained in position thereon. The securing means is readily adjustable to adapt itself to the various sizes of cables and the disk itself being slit in the manner shown and described is also adjustable. It is noted that when in position on the cable or hawser the disk is cone-shaped as may be seen from Figures 1 and 2 of the drawings. The attaching plates 22 are riveted adjacent their 20 ends to the disk and thus they have the further function of bracing and strengthening 25 the disk at the points where the greatest strength and rigidity is required.

I claim:

30 1. In a rat guard, a disk having a central opening adapted to receive a cable or the like, and means carried by the disk for securing it in position upon the cable and including a plurality of pivoted attaching arms, the attaching arms having eyes at their outer ends, a flexible element trained through said eyes, said arm having prongs adapted to engage the cable.

40 2. In a rat guard, a disk having a central opening adapted to receive a cable or the like, and means carried by the disk for securing it in position upon the cable and in-

cluding a plurality of pivoted attaching arms, the attaching arms having eyes at their outer ends, and a flexible element 45 trained through said eyes.

3. In a rat guard, a disk having a central opening and a radial slit, the radial edges adjacent said slit being overlapped, a catch cooperable with said overlapping edges and 50 means at the center of the disk adapted to coact with the cable or the like for securing the disk in position upon the cable and comprising a plurality of attaching arms, plates riveted to the disk and having pivotal connection with the attaching arms, eyes carried by the outer ends of the attaching arms, a flexible cable trained through said eyes, prongs carried by the attaching arms and adapted to engage the rope. 55

4. In a rat guard, a disk having a radial slit, the radial edges formed by said slit being overlapped and a catch cooperable with said overlapping edges including a keeper secured to one edge and overlying the other, said keeper having an inclined keeper plate, and a latch carried by the other of said edges and underlying the keeper and having an inclined latch plate cooperable with the inclined keeper plate. 60

5. In a rat guard, a disk having a radial slit, the radial edges formed by said slit being overlapped and a catch cooperable with said overlapping edges including a keeper secured to one edge and overlying the other, 75 said keeper having an inclined keeper plate, a latch carried by the other of said edges and underlying the keeper and having an inclined latch plate cooperable with the inclined keeper plate, and means at the center 80 of the disk for securing the disk in position upon a cable or the like.

ROBERT MALLU.
